UNITED STATES PATENT OFFICE

159,513

TOWEL BAR

Paul M. Pease, Pasadena, Calif., assignor to
Fletcher Manufacturing Company, Burbank,
Calif., a corporation of California

Application November 1, 1948, Serial No. 149,415

Term of patent 7 years

(Cl. D33—16)

To all whom it may concern:

Be it known that I, Paul M. Pease, a citizen of the United States of America, residing at 825 North Michigan Avenue, Pasadena 6, in the county of Los Angeles, State of California, have invented a new, original, and ornamental Design for a Towel Bar, of which the following is a specification, reference being had to the accompanying drawing, forming a part thereof.

I claim:

The ornamental design for a towel bar, as shown.

PAUL M. PEASE.
